DRESSING FORM FOR UNDERREAMER LUGS

Original Filed May 28, 1926

INVENTOR
C. H. Brown
BY *Murphy*
ATTORNEY

UNITED STATES PATENT OFFICE

CHARLES HENRY BROWN, OF BRECKENRIDGE, TEXAS

DRESSING FORM FOR UNDERREAMER LUGS

Original application filed May 28, 1926, Serial No. 112,350. Divided and this application filed September 22, 1927. Serial No. 221,338.

This invention relates to an improvement in dressing forms for underreamer lugs and constitutes a division of my application Serial Number 112,350, filed May 28, 1926, for an underreamer patented February 14, 1928, No. 1,659,514.

The object of the invention is to provide a device of this character which is particularly adapted for underreamers with bodies in which the lugs fit in such a manner that the shanks are so held in the body that the cutting portion of the lug or cutter can be dressed to correct gauge by re-forming it against the die portion of the dressing form, the dressing form having surfaces for the shanks of the lugs to fit in or against corresponding dimensions to the portion of the body holding the cutter while it is in a cutting position.

Another object of the invention is to so construct a form of this character whereby means are provided for insuring all the cutters of the set being dressed to the same length, therefore avoiding breakage of joints, ruining of bodies, or losing of lugs, or entire underreamers due to only one lug taking the blow in each stroke of the tools.

In carrying out these objects, the invention is susceptible of a wide range of modification without departing from the spirit or sacrificing any of the advantages of the claimed invention; there being shown in the drawings for illustrative purposes a preferred and practical form, in which:

Figure 1 represents a front elevation of a dressing form constructed in accordance with this invention;

Fig. 2 is a central longitudinal vertical section thereof showing how the blades are positioned and operated upon the dressing form; and

Fig. 3 is a similar view showing a slightly different manner of mounting the die on the body of the form.

In the embodiment illustrated a dressing form is shown comprising a base 1 which may be suitably supported as indicated at 2 the bottom of which is inclined so as to set on a slant to facilitate dressing the lugs and which has a surface 3 to support the shank of

the cutter, and a surface 4 to support the body thereof, a steel die 5 being provided against which the cutting portion of the blade may be re-formed. This die 5 is preferably cast integral with the chilled surfaces and ground.

The base 1 of the dressing form has a cylindrical portion 6, the lower part of which presents the surface 3 and this cylindrical portion carries a clamping screw 7 which is engageable with the shank of the blade to clamp the same firmly in position on the dressing form.

If the shoulder 11 of the blade has become worn, a number of shims S may be interposed between the shoulder of the blade and the shoulder 8 provided on the base 1 of the dressing form between the surfaces 3 and 4.

When the reamer blade B has been clamped on the base of the dressing form shown by the screw 7, its cutting portion overlies the die 5, and the metal making up the cutting portion may be forced up against the die to renew and re-form the cutting edge. In Fig. 2 a fuller F is shown placed against the cutting portion, and when this fuller is struck with a sledge hammer, the cutting portion will be displaced against the die and re-formed on its outside and the cutting face formed flush with the die and be perfectly true and with all the cutters of one set dressed with the same shims behind the shoulder all will be exactly the same length. Of course, the cutter or blade is heated before being placed in the dressing form.

In the form shown in Fig. 3 the die 5 is secured to the base 1 by means of screws 8a and the die rests on an underlying supporting rib 9.

It will thus be seen that by the use of a dressing form constructed as herein shown and described that the shanks of the lugs are so held in the body that the cutting portion of the lug or cutter can be dressed to correct gauge by re-forming it against the die portion of the dressing form, which dressing form has surfaces for the shanks of the lugs to fit in or against them corresponding to the dimensions of the portion of the body holding the cutter while it is in a cutting posi-

tion, the dressing form having clamping means to hold the cutter securely while it is being dressed. By using the shims S to compensate for wear all of the cutters of a set may be dressed to the exact gauge and also to the same length. This dressing of the cutters to the same length prevents much breakage of joints, as well as the ruining of bodies and losing of lugs, which is often occasioned when one lug only takes the blow at each stroke of the tool.

Without further description it is thought that the features and advantages of the invention will be readily apparent to those skilled in the art, and it will of course be understood that changes in the form, proportion and minor details of construction may be resorted to, without departing from the spirit of the invention or its scope as claimed.

20 I claim:—

A dressing form for use in connection with reamer blades having shanks with rounded backs; said form including a base having surfaces cooperable with the cutter and shank 25 of the blade to be dressed and having a die against which the cutting edge of the blade may be re-formed, said base having a shoulder between the surfaces thereof which supports the cutter and shank of the blade, said 30 shoulder being designed to coact with the shank of the blade of the body thereof, said blade having a shoulder at the junction of its shank and body, said base having its 35 bottom inclined to position the form on a slant to facilitate dressing of the lugs and shims interposable between said shoulder and the shoulder of the blade to cause the cutters to be positioned according to the wear of the material on the cutting edge thereof to insure 40 all the cutters of a set being dressed to the same length to avoid breakage of joints, ruining of bodies, or losing of lugs, incident to one lug only taking the blow in each stroke of the tool.

45 CHARLES HENRY BROWN.
